BOTTLE SEAL CUTTING AND TRIMMING DEVICE

William F. Ross, Chicago, Ill., assignor of one-half
to John R. Bayston, Chicago, Ill.

Application October 17, 1941, Serial No. 415,497

4 Claims. (Cl. 30—2)

This invention relates to a bottle seal cutting and trimming device.

As is well known, many liquids today are placed in bottles which are closed by means of a stopper of cork or other suitable material, the stopper being provided with an outwardly extending flange which seats upon the top of the neck of the bottle when in place. Over the stopper and the neck of the bottle is then placed a seal of metal, cellulosic or other material, and hence, to open the bottle, it is necessary to cut or otherwise destroy the seal, as, for example, by placing a knife or other sharp instrument adjacent the space where the top of the neck of the bottle and the underside of the flange of the stopper meet, the severing of the seal being, of course, effected by forcing the knife or other instrument inwardly and relatively rotating the bottle and the knife.

The disadvantage of this procedure, however, is that as the seal is severed flush with the top of the bottle a jagged edge is left around the latter which interferes with the pouring of the contents of the bottle, and in some cases, even leads to particles of the seal becoming mixed with the contents.

It is accordingly an object of the present invention to overcome the above recited disadvantage and to provide a simple, inexpensive and yet effective device or tool with which, in a simultaneous operation, the seal and other covering material of a bottle can be broken or cut at the point where the top of the bottle and the underside of the flange and stopper meet and which will perform a trimming action upon the seal so as to remove the jagged edge just above referred to by cutting the seal back to a point below the mouth of the bottle.

Further objects of the invention will become apparent from the following description of the device which is given by way of example only, it being understood that any modification within the scope of the invention may be utilized without departing from the spirit thereof.

In the drawing:

Fig. 1 is a perspective view of the tool or device constructed according to the present invention.

Fig. 2 is a side elevational view showing the device in use.

Fig. 3 is a cross section through the top of a bottle and stopper and seal therefor with the present device, also in cross section, in operative position, and

Fig. 4 is a section taken on the line 4—4 of Fig. 3.

The device of the present invention comprises a somewhat short length of spring metal 2, which is bent back upon itself as at 4 to provide a substantially U- or V-shaped device with two spaced apart arms 6, 8, one (6) of which is curved outwardly as at 10, then inwardly as at 12, and finally outwardly again as at 14, this arrangement providing surfaces which conform to and will readily receive and act as a guard for the thumb when the device is held in operative position in the hand for use. The other arm (8) of the device is likewise turned or bent outwardly as at 16 and thereafter follows the arc of a circle as at 18, this arrangement providing a convenient seat for one of the fingers of the operator, preferably the first finger.

At the upper edge of the arm 8 of the device, preferably mid-way of the arc 18, there is provided a cutting device 20 which, as shown, can conveniently be of triangular shape and formed by turning inwardly a portion of the metal of the said arm 8. The under surface or bottom edge of the arm 8 is provided with a second cutting edge 22 and here again this edge may be triangular in shape and be formed by bending over inwardly the metal of the arm itself. Preferably the cutting edge 22 is disposed slightly forwardly of the cutting edge 20. (See Fig. 4.)

Preferably the arm 8 for some portion of its length is divided by means of a slit or cut 24, which in the present instance is shown as extending from the tip of the arm 8 rearwardly for about 50% of the length of the arm and this for a purpose which will hereinafter appear.

When it is desired to use the tool or device, it is placed about the neck of a bottle or other container to be opened with the upper cutting edge 20 in line with the junction of the top or mouth of the container and the underside of the flange of the stopper and then its unconnected extremities are pressed inwardly firmly by the thumb on the arm 6 and by the finger on the arm 8. The bottle and the device are rotated relative to one another by the operator with the result

that the said cutting edge 20 will sever the seal and any other covering material circumferentially of the bottle at the junction above referred to. At the same time, this rotation of bottle and device will move the lower cutting edge 22 about the seal and other material, if any, at a point below the top or mouth of the bottle and hence cut the seal back to such point.

The advantage of dividing the arm 8 horizontally for a portion of its length is to permit the lower portion of the arm carrying the cutting

edge 22 to adjust itself to any protuberances with which the bottle neck may be provided, for example, in many bottles the neck just below the top thereof is provided with a depressed ring or slot which extends circumferentially around the neck. In the case of such a bottle, the dividing of the arm 8 would allow it to be adjusted to a different plane so that the cutting edge 22 will operate effectively upon the seal which in the case of a bottle so constructed, would be depressed into said ring or slot. This makes the device adaptable to a large range of bottle necks and corks of varying sizes.

It will be appreciated that by varying the width of the arm 8, the distance between the upper and lower cutting edges 20, 22, can also be varied.

By the present invention a bottle opener has been provided which will effectively remove or cut away a seal at a plurality of desired places and thus when the bottle is opened, provide a clear neck which will facilitate the ready pouring of the contents of the bottle uncontaminated by the metal of the seal.

I claim:

1. A bottle seal cutting and trimming device comprising a length of spring metal doubled back upon itself to provide two spaced apart and op-

posed arms, one of said arms bearing a pair of spaced apart cutting edges whereby to cut a seal disposed about the neck of a bottle circumferentially in two places and means on said one arm to permit the device to be adjusted for use in connection with bottles of different sizes.

2. A bottle seal cutting and trimming device comprising a substantially V-shaped member of spring metal, the legs of said member being provided with inturned cutting edges disposed in different planes, whereby to cut and trim a seal about the neck of a bottle at vertically separated points.

3. A cutting and trimming device comprising a U-shaped member, one of the arms of which has a cutting edge disposed at each of its two opposed edges, whilst the other arm is shaped to act as a guard when the device is in use.

4. A bottle seal cutting and trimming device comprising a length of spring metal bent back upon itself to provide a pair of opposed arms, one of said arms being bifurcated and each of the resulting divided portions of the arm being formed, at its outer edge, with an inturned cutter, whereby to cut a seal disposed about the neck of a bottle in two vertically separated planes.

WILLIAM F. ROSS.
